UNITED STATES PATENT OFFICE.

JAMES HORRIDGE, OF BOLTON, ENGLAND, ASSIGNOR TO JOHN HETHERINGTON AND SONS LIMITED, OF MANCHESTER, LANCASTER, ENGLAND.

COMBING MACHINE.

Application filed March 7, 1923. Serial No. 623,849.

To all whom it may concern:

Be it known that I, JAMES HORRIDGE, a subject of the King of Great Britain, residing at 71 Westbourne Avenue, Bolton, in the county of Lancaster, England, have invented new and useful Improvements in or Relating to Combing Machines, of which the following is a specification.

The invention relates to improvements in or relating to combing machines and has for its object to provide improved means for applying pressure to the upper nipper and at the same time to the feed roller and for relieving such pressure at the times desired.

The arrangement of mechanism employed according to the present invention for attaining this end is illustrated in the accompanying drawings in which—1 represents the nipper arm, 2 represents the top nipper, 3 represents the bottom nipper, 4 represents the nipper plate or feed table, 5 represents the feed roller and 6 represents the arm or bracket carrying the feed roller 5.

7 represents a bar or platform which is fixed upon the end of an arm or lever 8 pivotally mounted at its other end upon a stud 9 carried by a suitable part of the frame 10 of the machine.

Pivottally mounted upon a fixed arm or bracket 10^a carried by the frame 10 of the machine is a hand lever 11 provided with a handle 11^a by means of which it may be manipulated and with an arm or offset 11^b preferably having at its end a curved or cam surface as shown which in the position of said hand lever shown in the drawings supports the arm or lever 8.

Connected by one end with the end of the nipper arm 1 which is pivotally mounted at 20 ^a in the usual manner is a spring 12 the other end of which is connected to a V shaped bar or equivalent 13 which rests upon the bar 7 as shown.

The arm or bracket 6 carrying the feed roller 5 which is pivotally mounted at 14 upon the frame 10 is provided with an extension 6^a to which is connected one end of a spring 15 the other end of which is connected to a V shaped bar or equivalent 16 which rests upon the bar 7 in a similar manner to the bar 13.

The springs 12 and 15 are arranged in such manner that a pull upon the end of the nipper arm 1 and the end 6^a of the feed

roller arm or bracket 6 is exerted and said 55 pull is adjusted to such strength that the requisite pressure will be applied to the nipper 2 and feed roller 5.

When it is desired to relieve said pressure the handle 11^a of the lever 11 is pulled 60 in the direction of the arrow by the attendant thus lowering the arm or offset 11^b when the lever or arm 8 follows the movement thereof and the outer end of said arm 8 carrying the bar 7 moves in a downward direction thus relieving the tension of the springs 12 and 15 and therefore the pressure upon the nipper 2 and feed roller 5 whilst by moving the handle 11^a in the opposite direction the pressure may be re- 70 stored.

It will be understood that the details of construction of the device may be modified without departing from the principle of the invention.

What I claim as my invention and desire to secure by Letters Patent is:—

1. In a combing machine, means for applying pressure to the top nipper and feed roller, comprising a pivotally mounted arm 80 or lever, springs connecting said arm or lever with the nipper arm and feed roller bracket respectively, and movable means for supporting said arm or lever against the pull of said springs substantially as herein 85 set forth.

2. In a combing machine, means for applying pressure to the top nipper and feed roller comprising a pivotally mounted arm or lever, a bar or platform carried thereby, 90 a spring at one end connected with the nipper arm and at the other end with said bar, an extension to the feed roller support, a spring at one end connected with said extension and at the other end with said bar 95 and means for supporting said arm or lever against the pull of said springs and removing said support at the times desired substantially as herein set forth.

3. In a combing machine, means for applying pressure on the top nipper and simultaneously to the feed roller comprising a pivotally mounted arm or lever, a bar or platform carried by the outer end thereof, a spring at one end connected with the nipper arm and at the other end with said bar, an extension upon the feed roller support, a spring at one end connected with said ex- 100 105

tension and at the other end with said bar, a fixed arm or bracket carried by the frame of the machine, a hand lever pivotally mounted upon said arm or bracket, an arm or offset from said lever adapted to engage and support the first mentioned arm or lever against the pull of said springs, the ar-

rangement being such that upon turning hand lever upon its axis in one direction of motion the tension of said springs will be relieved substantially as herein set forth.

In testimony whereof I have signed my name to this specification.

JAMES HORRIDGE.
